[57] **CLAIM**

The ornamental design for a foldable display case for watchband calendar cards or the like, substantially as shown and described.

DESCRIPTION

FIG. 1 is a perspective view of a foldable display case for watchband calendar cards or the like showing my new design;

FIG. 2 is a left side elevational view thereof;

FIG. 3 is a top plan view thereof;

FIG. 4 is a bottom plan view thereof;

FIG. 5 is a rear elevational view thereof;

FIG. 6 is a top plan view of the interior thereof in unfolded position;

FIG. 7 is a bottom plan view of the exterior thereof in unfolded position;

FIG. 8 is a side elevational view thereof in unfolded position;

FIG. 9 is a front elevational view thereof in completely folded position;

FIG. 10 is a rear elevational view thereof;

FIG. 11 is a front edge elevational view thereof; and

FIG. 12 is a left side elevational view thereof.
